UNITED STATES PATENT OFFICE.

EDWIN H. DERRY, OF ERIE, PENNSYLVANIA.

DESIGN FOR A WASTE-BASKET.

52,158.

Specification for Design.

Patented July 9, 1918.

Application filed January 11, 1918. Serial No. 211,441. Term of patent 7 years.

To all whom it may concern:

Be it known that I, EDWIN H. DERRY, a citizen of the United States, residing at Erie, in the county of Erie and State of Pennsylvania, have invented a new, original, and ornamental Design for Waste-Baskets, of which the following is a specification, reference being had to the accompanying drawings, forming a part thereof.

The drawing is a perspective view of a waste basket showing my design.

I claim as new and desire to secure by Letters-Patent:

The ornamental design for a waste basket as shown.

EDWIN H. DERRY.
